UNITED STATES PATENT OFFICE.

THOMAS W. MOORE, OF NEW YORK, N. Y., ASSIGNOR TO FANNIE N. MOORE, OF SAME PLACE.

IMPROVEMENT IN COMBINED BUREAUS, WASH-STANDS, AND WARDROBES.

Specification forming part of Letters Patent No. 137,380, dated April 1, 1873; application filed January 18, 1873.

To all whom it may concern:

Be it known that I, THOMAS W. MOORE, of the city, county, and State of New York, have invented a new and Improved Combined Bureau, Wash-Stand, and Wardrobe, of which the following is a specification:

My invention consists of an upright wood case, divided vertically in two principal compartments, one of which is devoted to the purposes of a wash-stand in the lower part, and a bureau in the upper part, and the other is, by preference, devoted to the purposes of a wardrobe, but may have drawers instead, the wash-stand part being provided with supports for the wash-bowl and soap-dish, which swing out from under the drawers above when a door which incloses the front is opened; also, with special places for the other articles of crockery-ware appertaining to a dressing-room. A door is also provided for the wardrobe when used as such. The object is to combine either two or three of the principal articles of the furniture of a room in one, so as to economize space and expense.

Similar letters of reference indicate corresponding parts.

A is the said inclosed upright case, which is divided vertically into two principal compartments by the partition B. The part on one side of this partition—say the left—is divided horizontally by the partition C, forming a compartment, D, for the purposes of a wash-stand, and another, E, for one or more bureau drawers for containing linen. The compartment F on the left hand will, by preference, be used as a wardrobe, having hooks G for hanging the clothes, and a door, H, for closing it; but by dispensing with the door and hooks, drawers may be fitted in it, in which case a bureau and wash-stand only will be comprised in the article, the bureau having large capacity; but it will probably be more desirable to include the wardrobe, and increase the drawer capacity, if necessary, by additional drawers on the top, as indicated by the dotted lines. In the wash-stand compartment D, I provide a swinging frame, J, for the wash-bowl, and another, K, for the soap-dish near the top; and at the bottom I arrange a stand, L, for the water-pitcher, on one side of which will be a space, N, for the slop-pail, and beneath it a space for the mug.

Having thus described my invention, I claim as new and desire to secure by Letters Patent—

The bureau, wardrobe, and wash-stand, embraced in one article, and respectively arranged as and for the purpose described.
